UNITED STATES PATENT OFFICE

EMIL RICHTER, OF WYOMISSING, PENNSYLVANIA, ASSIGNOR TO TEXTILE MACHINE WORKS, OF WYOMISSING, PENNSYLVANIA, A CORPORATION OF PENNSYLVANIA

REBOUND STOP FOR STRAIGHT KNITTING MACHINES

Application filed December 21, 1929. Serial No. 415,746.

This invention relates to rebound preventing devices for knitting machines and the like.

An object of my invention is to provide 5 novel automatic rebound preventing means for machines in which one or more elements are reciprocatively actuated and strike against movement limiting stops; such for example as the thread carrier rods of straight- 10 knitting machines.

Another object is the provision of novel means in a full fashioned stocking knitting machine cooperative with certain of its thread carrier rod control members to accomplish additional control functioning thereof. 15

The invention comprises the novel elements, features of construction and arrangement of parts in operative relationship, for 20 attaining the above and other objects, as herein exemplified by one embodiment, while its scope is more particularly pointed out in the appended claims.

Further objects and attendant advantages of the invention will become more readily apparent from the following detailed description, reference being had to the accompanying drawings in which—

Fig. 1 is a fragmentary rear elevational view of one end of a full fashioned stocking 30 knitting machine having my invention applied thereto.

Fig. 2 is a fragmentary perspective view of the plating bar of the machine, the same being swung through an angle of approximately 180 degrees from the position shown in Fig. 1, in order to more clearly show the novel cam elements mounted thereon.

Figs. 3 and 4 are fragmentary cross-sectional views taken substantially as indicated by the arrows 3—3 and 4—4 on Fig. 1, and show certain cam elements in operating position.

Figs. 5 and 6 are diagrammatic illustrations 45 showing the extreme positions of a thread

carrier rod in conjunction with its movement limiting and associated control members.

Fig. 7 is an enlarged fragmentary detail view of a thread carrier rod and associated control elements.

Only such well known parts of a full fashioned stocking knitting machine generally involved in and showing the application of the invention have been illustrated; its operation being exemplified in connection with the plating carriers during the forming of the heel tabs. 50

The usual thread carrier rods 10, having abutment members or dogs 11, are reciprocated in timed relation with the plating bar 60 12, by the coulier mechanism, not shown.

Common end stops 13 and splicing stops 14 determinedly limit the distance of travel of the carrier rods 10 in accordance with the length of the thread feeding stroke required 65 to obtain desired fabric effects.

It has been found, that when the speed of the machine is increased beyond a certain point during attempts to increase its production, the thread carrier rods 10 which are not 70 controlled by shock or momentum absorbing means, strike against their respective movement limiting stops with such force that the resultant rebound action becomes excessive, and the well known frictional connection between the carrier rods and the friction rod yields, resulting in untimely retroactive movement of the rods 10 with consequent breakage of needles, sinkers and threads. 75

To obviate this difficulty, I provide for additional functioning of certain of the carrier rod control members of the machine, to obtain a latch mechanism which locks the carrier rods—in the present instance the plating carriers—against rebound movement when 80 striking their respective stops.

A carrier rod arresting and releasing crank lever 15, pivotally mounted on a rod 22 and movable in a finished slot of a bearing member 16, fixed to a spindle moved nut 17, has 85 90

its rod retaining arm 15a provided with a square opening through which the dog 11 on the plating carrier 10a passes when the lever is raised, while its other downwardly extending arm 15b is acted on by a vertically shiftable cam member 18 secured to the free end of a leaf spring 19, fixed to the plating bar 12 at 20.

10 A similar lever 21 is fulcrumed on the fixed rod 22 and acted on by a cam member 23 which is pivotally mounted in a slot of a bearing 24 adjustably secured to the plating bar by screw bolts 25. A tension spring 26 normally retains the cam member 23 in contact with an abutment edge 27 on the bearing.

20 When the plating bar 12 moves to the right as seen in Fig. 1, the edge 18a of cam 18 engages the lever arm 15b and operates the lever 15 to properly release the plating carrier 10a for movement to the right, (see Fig. 4). On the return stroke of the plating carrier, the lower extremity of lever arm 15b rides on the inclined part 18b of cam 18 and depresses the latter against the action of leaf spring 19.

30 A similar but reverse action takes place between lever 21 and cam member 23. When the plating bar moves to the left as seen in Fig. 1, cam edge 23a of cam 23 shifts lever 21 to properly release the plating carrier for movement to the left, while on the return stroke the lever swings the cam member about its pivot against the action of spring 26.

35 It will be noted that each of the cam members 18 and 23 function to actuate the respective levers 15 and 21 only once during each reciprocation or cycle of operation of the plating carrier 10a, for properly releasing 40 the same during its to and fro movement.

The purpose of providing for the periodic inactivity of the cam members 18 and 23, is to allow cam edges 11a of the abutment member 11 to engage with and lift the respective 45 levers 15 and 21 when passing thereunder, and permit the latter to drop and wedge in self adjusting position along the inclined rear edge 11b of the rebound-abutments 11 simultaneously with the striking of the rod 10a against one of the stops 13 and 14, as the case may be; thereby preventing retroactive movement of the plating carrier.

50 This action is shown diagrammatically in Figs. 5 and 6; the parts just described being 55 illustrated in their various positions during one cycle of operation of the plating carrier 10a. Fig. 5, shows the rod 10a at the moment it strikes against its end stop 13, and the manner in which it is locked against rebounding by the lever 15, while Fig. 6 shows an abutment member 11 striking against a stop 14, and the carrier 10a locked against rebounding by the lever 21.

60 In this manner, the cam elements 18 and 23 cooperate to properly release the plating

carrier 10a and time the beginning of its stroke in both directions, while the rod retaining members or arresting levers 15 and 21 function as latches during the inactive period of the cam elements, which are raised by and drop in self adjusted position behind the rebound-abutment members or dogs 11, to hold the carrier locked against movement in the opposite direction. The similarly inclined cooperating edges of the dogs 11, (see Fig. 7) and those of the levers 15 and 21, permit of self adjusting movement to automatically compensate for any wear, or play incidental to inaccurate adjustment, and therefore assure of proper locking 80 contact at all times during operation.

Similar rod rebound preventing mechanism is provided at the other end of the machine, which is cooperatively timed to 95 act in producing desired plating effects, in well known manner.

Of course, the rebound control mechanism herein specifically exemplified, may be changed and modified in various ways without departing from the invention disclosed, and changes may be necessary and desirable under certain conditions, it is therefore to be understood that the invention is not limited to the precise construction and arrangement set forth, but that such changes and alterations may be made as fairly come within the scope of the appended claims.

I claim:

1. In a straight-knitting machine, the combination with a reciprocatively operated thread carrier rod, and thread carrier rod abutment stops for stopping the rod at each end of its stroke; of a rod retaining lever operative to control the starting time of its stroke, and means on said rod actuating said lever.

2. In a straight-knitting machine the combination with a reciprocatively operated thread carrier rod, and thread carrier rod abutment stops for stopping the rod at each end of its stroke; of a rod retaining member operative to control the starting time of its stroke in one direction, means actuating said member to release the rod, and member operating means on the rod operative on the return stroke of the same.

3. In a straight-knitting machine, the combination with a reciprocatively operated thread carrier rod, and thread carrier rod abutment stops for stopping the rod at each end of its stroke; of rod retaining members operative to control the starting time of the carrier rod in either direction, means actuating said members to release the rod, and member operating means on the rod adjustably coacting with the members to prevent rebounding of the rod after striking the stops.

4. In a straight knitting machine having a reciprocatively operated carrier rod and

a fixed stop therefor; a rebound abutment on said rod; and a latch movable by said abutment into a position behind the latter for preventing rebound of said carrier rod after striking said stop.

5. In a straight knitting machine having a reciprocatively operated carrier rod and a fixed stop therefor; a rebound abutment on said rod; a latch movable by said abutment into a position behind the latter for preventing rebound of said carrier rod after striking said stop; and means operated by the rod reciprocative means for raising said latch from locking engagement with said abutment.

In testimony whereof I affix my signature.
EMIL RICHTER.
